TENSION BRAKE FOR BRAIDERS

George E. Henning, Baltimore, Md., assignor to
Western Electric Company, Incorporated, New
York, N. Y., a corporation of New York

Application April 28, 1933, Serial No. 668,302

4 Claims. (Cl. 96—13)

This invention relates to braiding machines and particularly to tension brakes for the strand supplies or cops.

The strand supplies or cops of a braiding machine are rotated at relatively high speeds by the pulling of the strands or threads therefrom during the braiding operation, and it is necessary to provide some means to maintain a constant tension or drag upon the strands or threads. The peripheral surfaces of strand supplies or cops are uneven and irregular due to the method of winding the threads or strands to form the same. The unevenness and irregularity of these surfaces increases as the diameter of the strand supplies or cops decreases. While the strand supplies or cops are rotating, it has been difficult and, in many cases, impossible to maintain a constant tension or drag upon the strands or threads as they are withdrawn from their supplies by the use of the ordinary paddle brake, especially as the strand supplies or cops are reduced in diameter. The unevenness and irregularity of the strand supplies or cops as they rotate continuously, oscillates the paddle brake, resulting in a loss or variation of the tension or drag of the strands or threads, as the brake is constantly being thrown outwardly and away from its contact with the peripheries of the strand supplies or cops.

The object of this invention is to provide a brake which will continuously contact with the strand supplies or cops to maintain a constant tension or drag on the strands or threads irrespective of the irregularities at the peripheries of the strand supplies or cops while the strands or threads are being withdrawn therefrom.

Other objects and advantages of the invention will be understood by reference to the following specification and accompanying drawing, in which

Fig. 1 is a plan view of a portion of a braiding machine embodying the invention;

Fig. 2 is a side view of Fig. 1;

Fig. 3 is an end view of Fig. 2; and

Fig. 4 is an enlarged sectional view taken on line 4—4 of Fig. 3.

In the drawing the invention is illustrated as applied to the outer or lower strand supplies or cops, although it is to be understood that the invention is equally adaptable to the inner or upper strand supplies or cops of the braiding machine.

The outer turret 10 of the braiding machine carries a plurality of thread guide supports 11, one associated with each strand supply or cop 12,

which carry at their outer extremities eyelets 13, and which also support intermediate their ends eyelets 14 and 15 for guiding the strands or threads 16 from the strand supplies or cops toward the braiding center. The outer turret 10 also carries a plurality of stationary shafts 17 to which are secured so as to rotate freely thereon the strand supply or cop holders 18. The strand supplies or cops 12 are secured to the holders 18 to rotate therewith by means of latches 19.

The bracket 20 secured to the outer turret 10 by means of bolts 21 adjacent to each strand supply or cop 12 is provided with an extension 22 to provide an adjustable supporting means 23 for the main brake support 24. The main brake support 24 has secured thereto an extended shaft 25 for rotatably supporting brake arm 26 and coiled tension spring 27 for the brake arm. The tension spring 27 has an extension 28 at one end bearing upon the brake arm 26 to force the same toward the strand supply or cop and at its opposite end an extension 29 passing into an aperture in adjusting nut 30. The nut 30, freely rotatable on the free end of the shaft 25, is for the purpose of regulating the tension of the spring 27, which in turn regulates the tension of brake arm 26. The nut 30 is provided with lugs and is held in locked position upon shaft 25 by means of a tapered pin 31 passing between the lugs and a hole through the shaft 25.

The brake arm 26 is provided with a brake shoe 32 at its outer end. This brake shoe 32 is formed with a concaved braking surface 33 which contacts with the strand supplies or cops 12.

The brake shoe is provided with extensions 34 and 35. The extension 34 has an aperture 36 therein through which the outer end 37 of the brake arm extends. The brake arm is provided with stops 38 against which the extension 34 of the brake shoe is held for vertical pivotal movements by spring 39, one end of which is secured thereto and the opposite end to the extension 40 of the brake arm 26. The extension 35 of the brake shoe 32 is formed with a relatively large aperture and stop lugs 41 to form a loose connection between the extension 35 and the brake arm 26. The lower wall forming the aperture 36 in the extension 34 of the brake shoe 32 is arcuate-shaped, as shown in Fig. 4, to permit a horizontal rocking movement, as well as a vertical pivotal movement, of the brake shoe.

The brake shoe 32 is permitted to rock and pivot on the brake arm 26, due to the arcuate surface 42 and the action of the spring 39.

In the operation of the braiding machine the strand supplies or cops 12 are rotated about their shafts 17. The brake arms 26, together with brake shoes 32 carried thereby, are forced toward the strand supplies or cops 12 by means of the extension 28 of spring 27.

The rocking and pivotal movements between the brake arms 26 and the brake shoes 32, permitted by the springs 39, together with the contacts between the arcuate surfaces 42 and the outer ends 37 of the brake arms 26, are such that the brake shoes will be held in continuous contact with the strand supplies or cops 12 irrespective of irregularities of the strand supplies or cops 12.

While the invention is illustrated and described more particularly with reference to tension brakes for braiding machines and the like, the invention is not confined thereto but is intended to cover any other uses or modifications within the scope of the appended claims.

What is claimed is:

1. In a braiding machine, a strand supply, a brake arm, pivotally movable toward and from the supply, an adjustable spring to control the tension upon said arm, a brake shoe carried by said brake arm in contact with the supply and with freedom to rock and pivot in two direc-

tions on the arm, and a spring for holding said brake shoe on said brake arm in rocking and pivotal relationship with respect to said brake arm.

2. In a braiding machine, a strand supply, a brake arm, a brake shoe carried by said brake arm having an aperture through which the brake arm extends, said brake shoe having an arcuate bearing surface at the contact thereof with the brake arm so that said brake shoe is free to both pivot and rock on said brake arm.

3. In a braiding machine, a strand supply, a brake arm, a spring for forcing said brake arm toward said strand supply, a brake shoe carried by said brake arm in contact with said strand supply and free for rocking and pivotal movements on said brake arm, and a spring for maintaining said brake shoe on said brake arm while permitting said rocking and pivotal movements.

4. In a braiding machine, a strand supply, a spring-pressed brake arm pivotally movable toward and from said strand supply, and a brake shoe having a spring connection with and carried by said brake arm in contact with said strand supply having freedom to rock and pivot in two directions on said brake arm to continuously contact with said strand supply.

GEORGE E. HENNING.
